(57) **CLAIM**

The ornamental design for an ergonomic keyboard with touch pad, as shown and described.

DESCRIPTION

FIG. 1 is a front view of the ergonomic keyboard with touch pad showing my new design.

FIG. 2 is a top view thereof;

FIG. 3 is a bottom view thereof;

FIG. 4 is a left side view thereof; and,

FIG. 5 is a right side view thereof.

The rear view is not shown as it is a generally flat surface with no distinctive texture or ornamental features.
